Primary Examiner—B. J. Bullock*Assistant Examiner*—Paula Mortimer*Attorney, Agent, or Firm*—Jones, Day, Reavis & Pogue[57] CLAIM

The ornamental design for a briefcase cover, as shown and described.

DESCRIPTION

FIG. 1 is a front perspective view of a briefcase cover showing my new design;

FIG. 2 is a front perspective view of a briefcase cover in a folded position;

FIG. 3 is a front elevational view thereof;

FIG. 4 is a rear elevational view thereof;

FIG. 5 is a top plan view thereof;

FIG. 6 is an end elevational view thereof;

FIG. 7 is an opposite end elevational view thereof; and,

FIG. 8 is a bottom plan view thereof.

The broken line showing of the handle in FIG. 1 is for illustrative purposes only and forms no part of the claimed design.
